GEORGE D'ANNUNZIO, OF JERSEY CITY, NEW JERSEY, ASSIGNOR TO SHOUP-OWENS, INC., OF HOBOKEN, NEW JERSEY, A CORPORATION OF NEW JERSEY

PASTEBOARD BOX

Application filed January 30, 1932. Serial No. 589,825.

This invention relates to the manufacture of boxes from pasteboard and the like, the box being of that type employed for holding cigars. The invention consists in a novel and useful box construction and aims at providing a novel distribution of strength to best withstand the particular strains to which such boxes are subjected providing adequate strength where required and avoiding waste of material at other points. Broadly speaking, my object is to produce a strong, serviceable, and attractive box at a minimum of cost and without sacrificing, in any particular, strength, durability, or appearance. When cigar boxes are packed, the cigars are first placed loosely therein and then crowded down under heavy pressure. This pressure tends to flatten and bulge all the cigars laterally, and this applies the greatest strain upon the end walls of the box, with little or no strain upon the front and rear walls thereof. Accordingly I construct the end walls of sufficient thickness to effectively withstand the aforesaid pressure without bulging. Added strength is also applied to the bottom of the box to prevent bulging after the usual cover has been closed down to hold the compressed cigars in place. The front and rear walls, which take little or no strain, I make of substantially less thickness and I thereby avoid a needless waste of material and save in cost of production and transportation. Again, by my improvements the work of making and putting together the constituent parts of the box is greatly simplified and speeded up, adding further to economy of production. Again, by reason of my improved construction, the edges of the finished box, instead of being more or less rounded, in the manner characteristic of many pasteboard boxes, are sharply defined, thereby simulating closely in appearance the edges of a relatively costly wooden cigar box. These and other advantages will be apparent to the mechanic skilled in this art from a reading of the following description and an examination of the accompanying drawing, in which—

Fig. 1 is a perspective view of the finished box with its outside paper wrapper;
Fig. 2 is a plan view of a pasteboard blank;

Fig. 3 is a plan view of another blank;
Fig. 4 is a perspective view of a detail on construction;

Fig. 5 is a plan view relatively enlarged of a box body, minus the outside paper wrapper; 55
Fig. 6 is a cross section on the line 6—6 of Fig. 5;

Fig. 7 is a cross section on the line 7—7 of Fig. 5;

Fig. 8 is a perspective view of one end of 60 the box body shown in Fig. 5.

The body of the box is formed primarily of two pasteboard blanks. One of these blanks is of cruciform outline and has four flaps which form, when folded up, the front, rear, and end walls of the box body. The other blank is of rectangular outline and has only two flaps, the same being located at the opposite ends thereof, and which, when folded up, cooperate with the bottom 65 and the end flaps of the first mentioned blank to substantially reinforce the same. 1 represents the central portion or body of the first mentioned blank. This portion 1 is for the bottom of the box body. 2—2 represents 70 end flaps on the body 1 which, when turned up, form the inside end walls of said box body. 3—4 represents side flaps on the body 1 which, when turned up, form the front and rear walls of said box body. When all of 75 these flaps are turned up into place to form said box body, they may be held in that position by the well known strong fabric corner stays, but preferably they are held by means of a rectangular strip 5 of strong 80 pasteboard which extends horizontally around the folded up flaps so as to firmly secure them after the manner of a strap. This strip 5 is preferably of a width corresponding closely to the height of the flaps 85 2—3—4 so that said strip itself will aid in reinforcing the front, rear, and end walls 90 of the box body. The rectangular blank is also formed of pasteboard preferably of a little less thickness than the first mentioned 95 blank, but, nevertheless, sufficiently thick so as to contribute substantially to the strength of the parts with which it is to be associated. The body of this second blank is indicated at 6, while 7—7 represents two flaps at the op-

100

posite ends of said body. By preference the width of the second blank, when it is to be located on the outside of the first blank, corresponds closely to the overall width of the box, and the height of the flaps 7-7 when turned up may be slightly greater than the height of the end flaps 2-2 of the first mentioned blank. Thus, with the second blank on the outside of the first blank, the upper edges of the flaps 7-7 will stand slightly above the upper edges of the end flaps 2-2. In that particular form of box body shown herein, when the box cover (later described) is closed, it will rest upon the ledges formed by the upper edges of the flaps 2-2 and between the upper edges of the flaps 7-7. Suitable adhesive material may be applied between all of the surfaces of the aforesaid elements of the box body to bind them firmly together to stiffen the walls formed thereby. When the box body is thus formed, it is customary to apply a final finishing wrapper, ordinarily of thin ornamental paper, to the exterior surfaces so as to give thereto the desired appearance. It is also customary to apply a suitable thin lining paper to the interior walls of the box body to finish the same. 8 represents a rectangular blank of pasteboard which is to constitute the box cover. This cover may be hinged at 9 by the usual fabric hinge strips, or otherwise, to the rear edge of the box body. The blank 8 may, of course, have the usual paper covering to hide the hinge strips and to give the desired appearance. Since, in its preferred form, the second blank with its two end flaps corresponds substantially in width to the overall width of the box (meaning the fore and aft dimension of the same), and since it is made of pasteboard of substantial thickness, it is apparent that when this blank is died out its edges will be sharp and firm so that when the box body is assembled and covered with said external wrapper, the lower front and rear edges, the upper end edges, and all four corners of the finished box will present sharp and well defined edges simulating closely the edges and corners of a relatively costly wooden box. By the term "pasteboard" I mean to include, of course, similar manufactured material, as distinguished from natural wood.

It will be noted by reference to Fig. 2 that the blank is scored inwardly slightly on the folding lines of the end flaps 2-2, so that when all four flaps are turned up the end flaps will bear squarely against the ends of the front and rear flaps 4-4, as shown in Fig. 5, so as to produce four sharp corners, around which the strap 5 will firmly and securely fit.

I wish to have it understood that I have shown and described my invention in its preferred form only, being aware that some changes and modifications may be made

without departing from the spirit thereof or from the scope of the following claims.

I claim:

1. A cigar box formed of two pasteboard blanks, one blank having two side flaps and two end flaps, all four flaps when folded up forming the sides and ends of the box body, means for holding said flaps in said folded up position, the other blank being located on the outside of said body and covering the bottom and ends only and cooperating therewith to increase the relative strength of said parts of the finished box, the second mentioned blank and its end flaps being of a width corresponding substantially to the overall width of the box body, the edges of said second blank forming all four corners, the front and rear lower edges, and the upper end edges, of said box body, and a thin wrapper covering for the corners and edges of said box. 70 75 80 85

2. A cigar box comprising a pasteboard blank having two end flaps and two side flaps, all four of which when folded up forming the bottom, ends, and sides of the box body, means to secure said flaps in said folded up position, a second pasteboard blank having flaps at its opposite ends only and cooperating with corresponding parts of the first blank to increase the relative strength of the bottom and ends of said box body, the width of said second blank corresponding substantially to the overall width of the box body, the height of the flaps on the second blank being slightly in excess of the height of the end flaps on the first mentioned blank with a thin paper wrapper for the edges and corners of said box body, and, with a cover hinged at its rear edge to the upper edge of the rear wall of said box body, said cover being of a length and width to rest upon the upper edges of the end flaps and the front flap of the first mentioned blank and between the extreme upper edges of the end flaps of the second mentioned blank when said cover is 100 105 110 closed. 115

3. A cigar box comprising a pasteboard blank having two end flaps and two side flaps, all four of which when folded up forming the bottom, ends, and sides of said box body, means to secure said flaps in said folded up position, said means comprising a pasteboard strap of a width substantially equal to the height of said flaps and secured to and extending horizontally around the sides and ends of said body, a second pasteboard blank having flaps at its opposite ends only and cooperating with corresponding parts of the first blank to increase the relative strength of the bottom and ends only of said box body, the width of said second blank corresponding substantially to the overall width of the box body, the height of the flaps on the second blank being slightly in excess of the height of the end flaps on the first mentioned blank, 120 125 130

- with a thin paper wrapper for the outside of said box body and with a cover hinged at its rear edge to the upper edge of the rear wall of said box body, said cover being of 5 a length and width to rest upon the upper edges of the end flaps and the front flap of the first mentioned blank and between the upper edges of the end flaps of the second mentioned blank when said cover is closed.
- 10 4. A cigar box comprising two pasteboard blanks, one being of cruciform outline to provide two side flaps and two end flaps, all four flaps when folded up meeting at their adjacent edges to form the main box body, 15 and a strap extending around said folded up flaps to hold the same in folded up position, said strap forming the top edges of the front and rear of the box, the other blank having two end flaps, said blank being of the width 20 of the finished box and overstanding, when its flaps are folded up, the bottom of the box body and also those parts of the strap that overlie the end flaps of said first mentioned blank, said second blank forming all four 25 corners of said box and the front and rear lower edges thereof.
